UNITED STATES PATENT OFFICE.

ERNON VELSOR OLIVER, OF PORTLAND, OREGON.

DISTILLING APPARATUS.

Application filed October 8, 1921, Serial No. 505,004. Renewed October 6, 1924.

This invention relates to a combined distilling and cooking apparatus and more particularly to an apparatus for employment in distilling water and cooking or canning articles of food.

One of the primary objects of the present invention is to provide in an apparatus of this class, a condensing medium which will present a condensing surface of maximum area to the water vapor generated within the apparatus and to so arrange this medium that the vapor condensed thereon will be delivered, without contamination, to a receiving trough forming a part of the apparatus from which trough the distilled water may be continuously withdrawn.

Another important object of the invention is to provide novel means for supplying cold water to the condensing medium in such a manner that the entire contained body of water within the medium will be kept constantly at a low temperature so as to increase the efficiency of the medium in condensing the generated vapors.

The invention also has as an important object to provide means for aerating the distilled water as it is accumulated in the receiving trough of the apparatus so that it will not have a flat taste and will therefore be more palatable than water distilled under other conditions.

Another object of the invention is to provide novel means for automatically maintaining a proper level of water within the well of the apparatus at all times during the operation of the same.

A further object of the invention is to provide the well of the apparatus with a bottom so constructed as to afford a heat radiating surface of maximum area and thus render more effective the generation of steam.

The invention also has as an object to so construct the walls of the body of the apparatus as to provide an auxiliary condensing surface and generally render the apparatus more efficient.

The invention also contemplates so constructing the apparatus that certain parts thereof may be selectively interchanged so as to adapt the apparatus to be put to a variety of uses.

The invention also has as a general object to provide an apparatus of the class stated which will be substantial and durable in

construction and yet inexpensive to manufacture and operate.

In the accompanying drawings:

Figure 1 is a perspective view of the apparatus embodying the invention, component parts thereof being shown relatively separated;

Figure 2 is a vertical longitudinal sectional view through the apparatus taken substantially on the line 2—2 of Figure 3;

Figure 3 is a horizontal sectional view taken substantially on the line 3—3 of Figure 2;

Figure 4 is a vertical transverse sectional view taken substantially on the line 4—4 of Figure 2;

Figure 5 is a plan view of a part of the apparatus upon which jars of fruit or the like may be deposited to rest during a canning operation;

Figure 6 is a vertical sectional view in detail taken substantially on the line 6—6 of Figure 1;

Figure 7 is a detail sectional view taken substantially on the line 7—7 of Figure 3.

The apparatus comprising the invention embodies an outer shell or body indicated in general by the numeral 1 within which is located the well for the impure water to be distilled, the trough for collecting the distilled water, and a removable condensing medium upon the walls or surfaces of which the generated vapor is to be condensed. The shell or body 1 comprises side walls 2, end walls 3 and 4, and a bottom 5 which constitutes also the bottom of the well of the apparatus, indicated by the numeral 6, and into which the impure water to be distilled is to be automatically fed as will be presently described. The said bottom 5 is preferably of the corrugated form illustrated most clearly in Figure 2 of the drawings so that it presents a heating surface of maximum area and thus increases the efficiency of the apparatus in generating water vapor or steam. Each of the side and end walls of the shell or body 1 comprises inner and outer wall sections 7 and 8 suitably united at their upper edges, as at 9, and spaced from their upper edges to a point a suitable distance above the bottom 5 where the outer section 8 is brought inwardly at an angle, as at 10, and thence downwardly in a plane parallel to the corresponding lower portion of the section 7 as at 11, the space between

105

110

the lower portions of the wall sections 7 and 8 being preferably filled with asbestos or other suitable heat non-conducting material 12. However the upper portions of 5 the said side and end walls are of the hollow construction illustrated in Figures 2, 3 and 4 of the drawings so as to provide a cold water space 13 completely surrounding the interior of the shell or body 1.

10 The upper portion of the well 6 is defined by a rectangular receiving trough indicated in general by the numeral 14 and comprising upstanding side and end walls 15 and 16 and a bottom wall 17, the walls 15 and 16 being spaced inwardly from the respective side and end walls of the shell 1, and the bottom wall 17 forming a juncture with the inner sections 7 of the said side and end walls of the shell. The trough is 15 open at its top and the walls 15 and 16 thereof preferably have their upper edges beaded, as indicated by the numeral 18. It will now be observed that the heat insulated lower portions of the side and end 20 walls of the shell 1 are of a height equal substantially to the depth of the well 6 whereas these walls above the top of the well are of the hollow construction previously described and providing the water 25 space 13. If desired, the sections 7 and 8 of the side and end walls of the shell 1 may be relatively braced in any suitable manner as for example by tubular or solid spacing elements 19 riveted or otherwise secured in place and extending between the 30 said sections within the water space 13.

Water is supplied, in the manner to be presently pointed out, to the water space 13, and in order that water may be delivered 40 from this space into the well 6 where, by the application of heat to the bottom 5 of the well, it is converted into steam and in order furthermore that the water in the well may be kept at a constant level and automatically 45 replenished, a float-controlled valve is provided and will now be described. The numeral 20 indicates in general a reservoir which is mounted in a fluid-tight manner upon the outer side of the end wall 4 of the 50 shell 1 and which comprises side walls 21, a front wall 22, and a bottom 23, the said reservoir in horizontal section being preferably rectangular. A water delivery tube 24 is rigidly supported within the reservoir 55 in upright position by suitable braces 25 or in any other manner found convenient and has in communication with it a branch 26 which communicates likewise with the water space 13 within the said end wall 4. The 60 upper end of the tube 24 projects above the top of the reservoir 20 and is closed by a cap 27 preferably threaded on to its upper end. At a point suitably spaced above its lower end, the tube 24 is provided interiorly 65 with a conical or tapered valve seat 28, and

the numeral 29 indicates an elongated valve body of corresponding form which is adapted to fit the seat 28 so as to close the tube 24, when the valve is elevated, and thus prevent delivery of water through the tube to the 70 reservoir 20. The valve is threaded at its lower end, as at 30, into a suitably formed socket 31 provided in the upper side of a float 32 located within the reservoir 20 below the lower end of the tube 24, this float 75 being preferably of rectangular form so that by engagement with the walls of the reservoir it will be prevented from turning in the event the valve 29 is rotated to unthread it from its socket 31. In order that the 80 valve may be guided and also in order that it may be rotated for the purpose of separating it from the float, it is provided at its upper end with a stem 33 which extends upwardly through the tube 24 and is of such 85 length that its upper end will project to or above the upper end of the said tube even when the float 32 is resting upon the bottom 23 of the reservoir 20 so that its said upper end may be gripped by a pair of pliers or 90 the like for the purpose stated. Likewise the cap 27 is of a height sufficient to accommodate the upper end of the valve stem when the float 32 and valve 29 are elevated to such position that the valve will fit its 95 seat 28. In order that water may be freely delivered from the tube 24, the said tube is not only open at its lower end, but is also provided below the valve seat 28 with a 100 number of water passages or openings 34. It is preferable that a wire or the like, indicated by the numeral 35, be soldered or otherwise secured in a horizontal plane to the inner sides of the walls of the reservoir 20 so as to indicate the proper water level 105 which should be maintained within the apparatus. A short tube 36 is fitted through the lower portion of the end wall 4 and establishes communication between the lower portion of the reservoir 20 and the well 6. 110 It will now be understood that water will flow from the water space 13 through the branch 26 and tube 24 and past the valve 29 and into the reservoir 20 from which it will be delivered, through the tube 36, into the 115 well 6 until the water reaches a predetermined level within the reservoir and well whereupon the float 32 will rise thus moving the valve 29 to its seat 28 and cutting off the supply of water until the level shall 120 again fall whereupon the float will lower and the valve will be automatically opened to effect a replenishment of the supply. In order to prevent escape of any steam from the reservoir 20 the top of the reservoir is 125 closed preferably by two hinged cover members one indicated by the numeral 37 and the other by the numeral 38, these members being respectively hinged, as at 39 and 40 to the end wall 4 of the shell 1 and the up- 130

per edge of the front wall 22 of the reservoir 20. The said cover members are cut away at their meeting edges, as indicated by the numeral 41, so as to accommodate the projecting upper end portion of the tube 24, and the edge of one member as for example the member 37 is provided with an upstanding longitudinal flange 42 overlapped by an overturned flange 43 formed along the meeting edge of the other member 38. The members 37 and 38 are also preferably provided at their end edges with depending flanges indicated respectively by the numerals 44 and 45 which are designed to fit over the upper portions of the side walls 21 of the reservoir. Thus the top of the reservoir is closed in substantially a steam-tight manner for the purpose stated.

In order that water may be drained from the well 6 whenever required, without the necessity of inverting the shell or body 1, a drain pipe 46 is led through the lower portion of the wall 4 of the said shell and is normally closed by a cap 47 threaded onto its upper end, a packing gasket 48 being provided within the cap to close the outer or discharge end of the said pipe 46 in a liquid-tight manner.

In order that the steam or water vapor generated within the well 6 may be delivered therefrom and distributed over the surfaces of the condensing medium, to be presently described, in the most effective manner, openings 49 and 50 are provided respectively in the side and end walls 15 and 16 of the receiving trough 14 a suitable distance below the upper edges of the respective walls, and a cover 51 is provided for the top of the well as defined by the space surrounded by the said walls 15 and 16. This top 51 comprises a plate 52 provided with a marginal depending flange 53 to seat over the beaded upper edges 18 of the walls 15 and 16, and with a depending flange 54 located inwardly of the marginal flange 53 which flange 54 likewise fits tightly against the inner surfaces of the beaded edges 18 of the said walls of the receiving trough. By the provision of this cover 51, the steam or water vapor generated within the well is trapped and caused to issue through the openings 49 and 50 and thus be discharged laterally rather than directly upwardly. However, the cover 51 is provided with any suitable number of openings 55 distributed in a selected way over the surface of the plate 52 and through which openings the steam or water vapor is likewise discharged in a general upward direction.

Preferably the side walls 15, and if desired also the walls 16, of the receiving trough 14 are braced with relation to the corresponding walls of the shell or body 1 by means of cross braces 56 preferably in the nature of strips secured in any suitable

manner at their ends to the said walls and extending between the same transversely of the trough. Also it is preferable that the trough be supported by small uprights 57 which project upwardly from the bottom 5 of the shell 1 and support the four inner corners of the trough. It will be understood, however, that the trough may be reinforced and supported or braced in various other ways if found desirable.

The condensing medium heretofore referred to is indicated in general by the numeral 58 and the same is in the form of a tank of peculiar construction into which water at a low temperature is caused to flow and in such a manner as to most effectually cool the walls or surfaces of the tank and thus condense the water vapor generated within the well of the apparatus and directed against these walls or surfaces. The said tank 58 comprises side walls 59, end walls 60, and a bottom which is indicated in general by the numeral 61 and which comprises upwardly inclined side portions 62 and upwardly inclined end portions 63, the side portions 62 meeting in a ridge 64, and the upper ends of the end portions 63 terminating at the ends of this ridge. Thus the said bottom is substantially of a pyramidal form and it projects upwardly into the interior of the tank a considerable distance. Likewise it will be observed by reference to Figures 2 and 4 of the drawings that the side walls 59 of the tank are inclined downwardly toward each other as are also the end walls 60 so that these walls occupy planes gradually diverging in a downward direction from the vertical planes occupied by the respective side and end walls of the shell 1. Therefore there is provided between the walls of the tank and the walls of the shell a steam space which is indicated by the numeral 65 and within which space the steam generated in the well of the apparatus may arise and by contact with the relatively cool walls of the tank and shell, be condensed and drawn into the trough 14, the condensate trickling down the sides of the walls of the tank and body and from the meeting lower edges of the walls of the tank and the side and end portions of the bottom of the tank. It will also be evident that due to the peculiar form given the bottom of the tank, a steam space 66 is provided within the said bottom and immediately above the top of the well 6. It will also be observed by reference to Figures 2 and 4 of the drawings that the meeting lower edges of the walls of the tank and bottom are

spaced somewhat from the walls of the trough 14 so that vapor condensing upon the walls of the tank and its bottom and trickling down these walls, may be discharged from the lower edges of the same without any interference on the part of the trough walls.

In order that the condensing tank 58 may be supported or suspended within the shell or body 1, the said tank is provided exteriorly near its top with a circumscribing horizontally outstanding supporting flange 67 preferably having a downturned outer marginal portion 68, this flange resting upon the top of the walls 2, 3, and 4 of the shell 1 and with its downturned margin 68 fitting snugly 5 against the outer sides of these walls so as to provide a substantially steam-tight connection between the parts. As stated the supporting flange 67 is located near the top of the tank 58 so that a portion of the tank 10 projects above the top of the shell or body 1, and to this projecting upper portion of the tank there is removably fitted a cover which is indicated in general by the numeral 69 and which comprises a top 70 having a 15 marginal portion 71 projecting downwardly at right angles and fitting snugly about the open top of the tank 58, from which portion 71 the margin of the top 70 is directed horizontally as at 72, and thence downwardly as 20 at 73 with the lower edge of this latter portion resting upon the upper side of the flange 67.

The manner in which cold water is continuously supplied to the tank 58 will now 25 be described. The numeral 74 indicates a nozzle or valved inlet pipe which is in communication with the water space 13 within the end wall 4 of the shell or body 1 and which may be connected with any suitable 30 source of water supply. By this means water is permitted to flow into the water space 13 and to fill said space, a regulated volume of water overflowing into the reservoir 20 and from the reservoir into the well 35 6. A short outlet pipe or nipple 75 is fitted through the top of the water space 13 at the top of the end wall 3 of the shell 1 and projects upwardly through a suitable opening (not shown) formed in the flange 67 of the condensing tank 58. The numeral 76 40 indicates the downward branching intake end of a water conducting pipe 77 which intake branch is disposed endwise to the upper end of the nipple 75 and connected in a water-tight and yet detachable manner thereto by means of a short piece of rubber tubing 78 or any other type of union. The pipe 77 has two downwardly extending legs 45 or branches. The branches 79 and 80 extend downwardly to one corner of the bottom of the tank 58 within the said tank, and the branch 81 leads from the lower end of the branch 79 along the adjacent end of the bottom of the tank 58, and a branch 82 leads 50 from the lower end of the branch 80 along the adjacent side of the bottom of the said tank. Branches 83 and 84 extend along the other side and end respectively of the bottom of the tank 58 and are in communication 55 with the branches 81 and 82 respectively and

join each other at the corner of the bottom diagonally opposite the corner at which the branches 79 and 80 are located. The several branches which are located within the condensing tank are formed with longitudinally 70 extending series of perforations 85 and it will be understood that the several branches constitute a closed circulating system through which cold water flows from the water space 13 of the shell 1, the water being 75 discharged in fine streams or jets through the perforations 85 and toward the walls of the tank 58 and its bottom 61. This supply of water is maintained even after the tank has become filled with water and therefore 80 through the medium of said pipe system, cold water is supplied to the condensing tank in a manner to well up from the bottom of the same along the walls of the tank and its bottom and thus maintain the said 85 walls and bottom at a relatively low temperature. An overflow pipe 86 is led through the projecting upper portion of one of the end walls 60 of the tank 58 and may have fitted to it a suitable length of rubber hose 87 to conduct the overflow from the tank to any suitable point of discharge. In order that sediment may be flushed from the water delivery pipe and its several branches above described, one of the branches as for 90 example the branch 84 is provided with a short upwardly projecting nipple 88 which may be closed by a removable plug or the like indicated by the numeral 89.

In order to adapt the apparatus for use 100 in steam cooking food stuffs as for example in jars or other containers, a tray such as illustrated in Figure 5 of the drawings and indicated in general by the numeral 90 is provided and this tray is preferably in the 105 form of a metal plate suitably reinforced at its margin, and elsewhere if desired, and provided with any desired number and arrangement of perforations 91 distributed over its area. When the apparatus is to be 110 employed for the purpose stated, the condensing tank 58 will be removed, the cover 69 separated therefrom, the cover 52 removed from the top of the well 6, the tray 90 disposed in position resting upon the top 115 of the well, as illustrated in dotted lines in Figures 2 and 4, and the cover 69 will then be fitted onto the top of the shell or body 1. With the apparatus thus arranged steam generated within the well will be discharged 120 through the perforations 91 in the tray and about the containers for the food stuff being cooked.

In the event it is desired to cook food stuffs in containers which are to be partly 125 submerged during the cooking operation, a tray indicated in general by the numeral 92 is disposed within the bottom of the well 6, the condensing tank 58 and cover 52 having been removed from the shell 1, and the 130

containers for the food stuff may be disposed upon this tray and within the well. The tray 92 comprises a plate 93 of rectangular form and of dimensions adapting it to be fitted downwardly through the top of the well 6 and similarly removed therefrom, and this plate is preferably overturned or beaded and reinforced by wire, as at 94 at its margin. The plate is formed with any suitable 10 number and arrangement of perforations 96 and thus the hot water may circulate freely past the plate and about the containers disposed thereon.

In order that water distilled by the apparatus may be aerated during the distilling operation and thus prevented from acquiring the flat taste which is so noticeable in water distilled by ordinary methods, means is provided which will now be described. 15 The numeral 97 indicates air supply pipes each having a horizontal branch 98 leading through the lower portion of one or another of the walls of the well 6, and a vertical branch 99 which leads upwardly from the inner end of the branch 98 and through the bottom of the trough 14 and upwardly into the trough a suitable distance. The upper portion of each branch 99 which is located within the trough 14 is formed with a number 20 of perforations 100 although the lower portion of the branch 99 which is located within the trough is imperforate. Thus inasmuch as the branches 98 and elbows of the pipes 97 are subjected to heat from the water being boiled in the well 6, the air within the pipes will be heated and in rising will create a draft or suction through the pipes resulting in a continual flow of substantially cold air inwardly through the pipes and through 25 the perforations 100, the air thus discharged serving to aerate the distilled water accumulating in the trough. In order that the outer or intake ends of the branches 98 or the pipes 97 may be closed when the apparatus is being employed solely as a cooker, the outer ends of these branches are threaded and have fitted thereto closure caps 101 preferably connected by short chains or other flexible connections 102 with the adjacent 30 walls of the shell 1 so as to prevent loss when they are unthreaded from the respective pipes.

By reference to Figures 2 and 4 of the drawings it will be observed that the bottom 35 17 of the receiving trough 14 is inclined downwardly from the end 3 to the end 4 of the shell and at that portion of the bottom wall which is located next adjacent the end wall 4 of the shell, is sloped downwardly 40 from its opposite sides to a point midway of its ends. A draw-off pipe 17^a opens through the central portion of this part of the bottom wall of the trough and is led through the wall 4 of the shell and is provided with a valve or faucet 17^b for controlling the flow

of distilled water through the pipe. It will furthermore be evident that because of the inclination of the bottom wall of the trough and the introduction of the draw-off pipe 17^a at the lowest point in the bottom, the trough may be completely drained. 70

A cut-off valve 26^a is preferably interposed in the branch supply pipe 26, as best shown in Figure 2 of the drawings, so as to control the supply of water fed to the reservoir 20, it being understood that this valve may be completely closed when desired, and the valve inlet 74 controlled so as to maintain a supply of water in the boiling well of less volume than would be maintained 80 through the automatic operation of the float controlled valve 29. Thus a relatively small volume of water may be maintained in the boiling well so as to provide for more rapid conversion of the water into steam and its 85 subsequent condensation.

By reference to Figures 2 and 4 of the drawings it will be observed that the pipe 86, interiorly of the condenser 58, is turned to extend downwardly at right angles as at 86^a and welded or otherwise secured as at 86^b to the inner side of the end wall 60 of the condensing tank, the lower end of this portion of the pipe however being deflected inwardly as indicated by the numeral 86^c so 90 as to provide for the attachment of a suitable length of rubber hose 86^d which leads downwardly to the bottom of the tank and which forms one leg of a siphon, the flexible hose 87 which is attached to the other end 95 of the over-flow pipe 86, constituting the other siphon leg and being led to any convenient point of discharge. By this arrangement all of the water from the condensing tank may be siphoned off without 100 noise. A valve 87^e is interposed in the pipe 86 exteriorly of the shell and may be adjusted so as to maintain a water level in the tank higher than the intake end 86^b of the pipe 86. 110

It will be understood that the upper ends of the branches 99 of the pipes 97 are closed so as to prevent distilled water dripping into these branches from the walls of the condensing tank. 115

Having thus described the invention, what is claimed as new is:

1. In apparatus of the class described, a shell having a well in its bottom, a receiving trough within the shell extending about the well, a cover for the well comprising a perforated cover plate having spaced marginally located flanges fitting and receiving between them the upper edges of the inner walls of the trough, the perforations in the cover plate providing means for the egress of steam from the well, and a hollow substantially pyramidal condenser within the shell having its bottom presented to the top of the well and having its inclined walls 125

terminating at their lower edges in position to discharge the water of condensation into the trough.

2. In apparatus of the class described, a shell having a well in its bottom, a receiving trough within the shell extending about the well, a cover for the well comprising a perforated cover plate having spaced marginally located flanges fitting and receiving between them the upper edges of the inner walls of the trough, the perforations in the cover plate providing means for the egress of steam from the well, and a hollow substantially pyramidal condenser within the shell having its bottom presented to the top of the well and having its inclined walls terminating at their lower edges in position to discharge the water of condensation into the trough, the said inner walls of the trough being also provided with openings for the egress of steam.

3. In apparatus of the class described, a shell having a well in its bottom, a receiving trough extending about the well, a condenser comprising a tank supported within the shell and having walls inclined downwardly and inwardly from the plane of the corresponding walls of the shell whereby to provide a steam space between the two, the condenser tank further comprising a bottom of hollow substantially pyramidal form having its walls inclined downwardly and outwardly and forming a juncture with the lower portions of the corresponding walls of the body of the tank, the bottom being presented to the top of the well, and means providing for egress of steam from the well through the inner wall of the trough and to the space above the well and trough.

4. In apparatus of the class described, a shell having a well in its bottom, a receiving trough extending about the well, a condenser comprising a tank supported within the shell and having walls inclined downwardly and inwardly from the plane of the corresponding walls of the shell whereby to provide a steam space between the two, the condenser tank further comprising a bottom of hollow substantially pyramidal form having its walls inclined downwardly and outwardly and forming a juncture with the lower portions of the corresponding walls of the body of the tank, the bottom being presented to the top of the well, means providing for egress of steam from the well through the inner wall of the trough and to the space above the well and trough, and a closure for the top of the well comprising a cover plate supported by the said walls of the trough and presented to the bottom of the condenser.

5. In apparatus of the class described, a shell having a well in its bottom, a receiving trough extending about the well, a condenser

comprising a tank supported within the shell and having walls inclined downwardly and inwardly from the plane of the corresponding walls of the shell whereby to provide a steam space between the two, the condenser tank further comprising a bottom of hollow substantially pyramidal form having its walls inclined downwardly and outwardly and forming a juncture with the lower portions of the corresponding walls of the body of the tank, the bottom being presented to the top of the well, means providing for egress of steam from the well through the inner wall of the trough and to the space above the well and trough, and a closure for the top of the well comprising a cover plate supported by the said walls of the trough and presented to the bottom of the condenser and having passages therethrough for steam generated within the well.

6. In apparatus of the class described, a shell having a well in its bottom and provided with a water space in its wall above the well, a receiving trough within the shell extending about the well, means for supplying water to the water space in the wall of the shell, a condenser tank within the shell above the well and arranged to deliver water of condensation to the trough, and means for conducting water from the water space of the shell to the interior of the said condenser tank.

7. In apparatus of the class described, a shell having a well in its bottom and provided with a water space in its wall above the well, a receiving trough within the shell extending about the well, means for supplying water to the water space in the wall of the shell, a condenser tank within the shell above the well and arranged to deliver water of condensation to the trough, and means for conducting water from the water space of the shell to the interior of the said condenser tank, the said means comprising a pipe extending about the lower portion of the interior of the tank and in communication with the said water space and provided with perforations for the discharge of water therefrom in the direction of a wall of the tank.

8. In apparatus of the class described, a shell having a well in its bottom and provided with a water space in its wall above the well, a receiving trough within the shell extending about the well, means for supplying water to the water space in the wall of the shell, a condenser tank within the shell above the well and arranged to deliver water of condensation to the trough, and means for conducting water from the water space of the shell to the interior of the said condenser tank, the said means comprising a pipe extending about the lower portion of the interior of the tank and in communication with the said water space and provided

with perforations for the discharge of water therefrom in the direction of a wall of the tank, the tank having an upwardly projecting bottom open at its lower side and presented to the top of the well and surrounded by the said pipe.

9. In apparatus of the class described, a shell having a well in its bottom and provided with a water space in its wall above the well, a receiving trough within the shell extending about the well, means for supplying water to the water space in the wall of the shell, a condenser tank within the shell above the well and arranged to deliver water of condensation to the trough, and means for conducting water from the water space of the shell to the interior of the said condenser tank, the said means comprising a pipe extending about the lower portion of the interior of the tank and in communication with the said water space and provided with perforations for the discharge of water therefrom in the direction of a wall of the tank, the pipe having a flushing nipple, and means for closing said nipple.

10. In apparatus of the class described, a shell having a well in its bottom, means within the shell to receive water of condensation, a condenser within the shell to deliver water condensed thereby to the said receiving means, a reservoir in communication at its lower portion with the well, a water supply pipe within the reservoir, a valve within the pipe for controlling the supply of water therethrough to the reservoir, a float controlling the valve separably connected therewith, and a stem extending from the valve upwardly through the pipe to a point accessible from the exterior of the pipe whereby the valve may be manipulated to separate it from the float.

11. In apparatus of the class described, a shell having a well in its bottom, means within the shell to receive water of condensation, a condenser within the shell to deliver water condensed thereby to the said receiving means, a reservoir in communication at its lower portion with the shell, a water supply pipe within the reservoir, a valve within the pipe for controlling the supply of water therethrough to the reservoir, a float for controlling the valve, the valve being separably connected with the float, a stem extending from the valve to a point accessible from the exterior of the pipe whereby the valve may be manipulated to separate it from the float, the upper end of the pipe extending exteriorly of the reservoir, and a cap removably fitted on to the said end of the pipe and receiving the upper end of the valve stem.

12. In apparatus of the class described, a shell having a well in its bottom, means within the shell to receive water of condensation, a condenser within the shell to deliver water condensed thereby to the said receiving means, a reservoir in communication at its lower portion with the well, a water supply pipe within the reservoir, a valve within the pipe for controlling the supply of water therethrough to the reservoir, a float for controlling the valve, the valve being separably connected with the float, a stem extending from the valve to a point accessible from the exterior of the pipe whereby the valve may be manipulated to separate it from the float, the upper end of the pipe extending exteriorly of the reservoir, and a cap removably fitted on to the said end of the pipe and receiving the upper end of the valve stem.

13. In apparatus of the class described, a shell having a well in its bottom, means within the shell to receive water of condensation, a condenser within the shell to deliver water condensed thereby to the said receiving means, a reservoir in communication at its lower portion with the well, a water supply pipe within the reservoir, a valve within the pipe for controlling the supply of water therethrough to the reservoir, a float for controlling the valve, the reservoir being open at its top and the said pipe extending at its upper end above the open top of the reservoir, and lid sections hingedly mounted at opposite sides of the open top of the reservoir and recessed at their meeting sides to accommodate the pipe.

14. In apparatus of the class described, a shell having a well in its bottom, means within the shell to receive water of condensation, a condenser within the shell to deliver water condensed thereby to the said receiving means, a reservoir in communication at its lower portion with the well, a water supply pipe within the reservoir, a valve within the pipe for controlling the supply of water therethrough to the reservoir, a float for controlling the valve, the reservoir being open at its top and the said pipe extending at its upper end above the open top of the reservoir, and lid sections hingedly mounted at opposite sides of the open top of the reservoir and recessed at their meeting sides to accommodate the pipe, said meeting sides of the section being provided with coacting flanges to provide a fluid-tight closure between the sections.

15. In apparatus of the class described, a shell having a well in its bottom, a receiving trough within the shell surrounding the well, a condenser tank removably supported within the shell above the well and in position to deliver water of condensation to the trough, a closure for the top of the well supported removably upon the wall of the trough, a foraminous tray adapted to be positioned within the shell to be supported by the wall of the trough after removal of the closure and the condenser tank, and a cover for the tank applicable also to the top of the shell.

In testimony whereof I affix my signature.
ERNON VELSOR OLIVER. [L. s.]
